UNITED STATES PATENT OFFICE.

ALEXANDER M. SCHNEIDER, OF NEW YORK, N. Y., ASSIGNOR, BY DIRECT AND MESNE ASSIGNMENTS, TO NEWTON EXTENSION PETTICOAT COMPANY, A CORPORATION OF NEW YORK.

SKIRT OR SIMILAR GARMENT.

1,009,262.

Specification of Letters Patent. Patented Nov. 21, 1911.

Application filed June 23, 1911. Serial No. 634,894.

To all whom it may concern:

Be it known that I, ALEXANDER M. SCHNEIDER, a citizen of the United States, residing at New York city, county and State of New York, have invented a new and Improved Skirt or Similar Garment, of which the following is a specification.

This invention relates to a skirt or similar garment and more particularly to novel and efficient means for adjusting its width at the waist. The construction is such that after a garment has once been adjusted it will retain its width even when taken off and without showing any objectionable fullness. When the garment is to be laundered it may however be expanded to its normal size, so that it may be properly washed and ironed.

In the accompanying drawing: Figure 1 is a rear view of the upper part of a skirt embodying my invention; Fig. 2 a front view thereof; Fig. 3 a horizontal section through the adjusting means, and Fig. 4 a front view of a somewhat modified construction of the skirt.

A skirt or similar garment 10 is provided with a waist band 11 having at a suitable portion of its length a plurality of spaced apertures 12. At a short distance from one of the last apertures the waist band is turned inward to form a fold 13 which fold is fastened down or fixed in suitable manner. As shown, the means for fixing the fold consist of the socketed member 14 of a spring clasp which passes through the doubled section of the waist band. The garment is further provided with a flap 15 that depends from the waist band, the outer edge of said flap coinciding substantially with the bight of fold 13. This flap extends downward along the inner side of the waist band and constitutes a pocket or inclosure for the doubled portion of the latter as hereinafter explained. To flap 15 is secured the headed member 16 of the spring clasp which cooperates with the socketed member 14. To shorten the waist measure of the garment, the waist band is tucked or doubled

underneath flap 15 to such an extent as to reduce the width of the garment to the proportions desired, Fig. 3, showing the entire apertured section of the waist band to be folded beneath the flap, but different adjustments may obviously be selected.

Care should be taken that during the tucking operation, one of the apertures 12 is brought into alignment with headed member 16, so that when the clasp is closed such member may pass freely through said aperture and into engagement with socket 14. After the clasp has thus been closed the size of the garment will become fixed; the intention being not to open the clasp during dressing, a placket 17 being provided for the latter purpose. When however the garment is to be laundered, the clasp is opened so that the inturned portion of the waist band may be straightened out.

In Figs. 1-3 flap 15 is shown to be formed between two apertured sections of the waist band, so that the latter may be tucked under both ends thereof.

In Fig. 4 a separate flap 15^a is shown to be formed at each side of the placket.

It is obvious that the invention is applicable to such garments other than skirts that require an adjustment of the waist. So also in lieu of permanently securing the fasteners to the garment, they may be made removable therefrom.

I claim:

1. A skirt or similar garment provided with a waist band having a plurality of apertures, a flap overhanging a portion of said waist band and forming a pocket for accommodating a doubled section thereof and securing means for said flap which are adapted to engage either one of the waist band perforations.

2. A skirt or similar garment provided with a waist band having a plurality of spaced apertures, a flap on the garment that projects over the waist band, a first fastening member carried by the waist band, and a second fastening member carried by the flap, one of said fastening members

being adapted to be projected through one of said apertures into engagement with the other fastening member.

3. A skirt or similar garment provided
5 with a waist band having a fixed fold and a plurality of spaced apertures at one side of said fold, a flap on the garment that projects over the waist band opposite the

fold, and fastening means on the fixed fold of the waist band and on the flap that are 10 adapted to be projected through one of said apertures.

ALEXANDER M. SCHNEIDER.
